UNITED STATES PATENT OFFICE.

HARRY D. YERXA, OF CHICAGO, ILLINOIS.

ATTACHMENT FOR COIN-CONTROLLED MECHANISM FOR VENDING-MACHINES.

1,178,370.

Specification of Letters Patent.

Patented Apr. 4, 1916.

Application filed December 23, 1915. Serial No. 68,417.

To all whom it may concern:

Be it known that I, HARRY D. YERXA, a citizen of the United States, residing at Chicago, in the county of Cook and State of Illinois, have invented certain new and useful Improvements in Attachments for Coin-Controlled Mechanism for Vending-Machines; and I do hereby declare the following to be a full, clear, and exact description 5 of the invention, such as will enable others skilled in the art to which it appertains to make and use the same, reference being had to the accompanying drawings, and to the letters and figures of reference marked 10 thereon, which form a part of this specification.

This invention relates to new and useful improvements in attachments for coin-controlled mechanism used for vending articles 20 and the object in view is to produce a simple and efficient device designed as a safeguard to prevent more than one coin being inserted in the machine at the same time, thus rendering it necessary to depress a lever 25 and operate the machine before the second coin may be inserted and utilized in the operation of the apparatus.

My invention comprises various other details of construction, combinations and arrangements of parts which will be hereinafter fully described, shown in the accompanying drawings and then specifically defined in the appended claims.

I illustrate my invention in the accompanying drawings, in which:

Figure 1 is a rear view of a portion of the coin-controlled mechanism showing the application of my invention thereto. Fig. 2 is a similar view showing the lever depressed 40 and the parts raised to elevated position. Fig. 3 is an enlarged detail view in side elevation showing the means for holding the coin and tripping the same. Fig. 4 is a similar view in elevation showing the coin held 45 from entering the slot. Fig. 5 is a view showing the lever depressed and the coin still held from entering the machine before the lever is released. Fig. 6 is a detail view of one of the coin arresting devices. Fig. 7 50 is a perspective view of a bracket arm which supports the coin arresting member and pawl. Fig. 8 is a detail view of one of the coin arresting members, and Fig. 9 is a detail view of a pawl.

Reference now being had to the details of the drawings by letter, A designates the

front wall of the casing of the coin-controlled machine and B a bracket arm secured thereto and which has pivotally mounted upon the pins D thereof the flanged plate C 60 upon which a coin is adapted to be deposited, preparatory to the successful operation of the apparatus, and a coin chute E is formed integral with said plate and is disposed at an inclination. Said chute has a 65 flange E' upon one edge thereof, and F is a lever pivotally mounted upon the pin F' upon the bracket arm H which is struck up from the front wall of the frame. A tilting member G is pivotally mounted upon a pin 70 G' carried by said flanged plate and has a laterally projecting portion G² upon which the coin is adapted to rest when inserted in the machine, and a spring G³ is fastened at G⁴ to the frame and its other end to an integral hook G⁵ upon the member G and 75 serves to normally return the same and the lever F to their normal positions. Said lever carries a pivotal pin I in oppositely disposed flanges and to which a link J is pivoted at its upper end and its lower end pivoted to the flange of the plate C by means of the pivotal pin N.

A bracket member L is fastened to the casing by means of rivets L', shown in Figs. 1 85 and 2 of the drawings, and has a wing L², apertured as at L³ for the reception of a pivotal pin O upon which a coin arresting plate Q is mounted, a detail of which plate is shown in Fig. 8 of the drawings, and 90 which is provided with a lug Q' struck up from one edge and has a lateral projection Q² upon its opposite edge and at its extreme widened end has an elongated slot Q³. A pawl, designated by letter R, a detail of 95 which is shown in Fig. 9 of the drawings, has an aperture R' therein through which a pivotal pin R² passes, which is carried by the bracket member L, and said pawl is notched as at R³, which notch is adapted to 100 engage the lug Q' when the pawl is in its normal position. A second coin arresting member, designated by letter S, a detail of which is shown in Fig. 6 of the drawing, is pivotally mounted upon the pivot O and 105 provided with a finger S', which is slightly curved and has its forward edge S² inclined slightly and is in the path of the flange E', shown clearly in Figs. 1 and 2 of the drawings. Said member S has an elongated 110 curved slot S³ thereon and through which and the slot Q³ the pin R² passes and which

pin, passing through the two curved slots, serves as a means for limiting the throw of the two members, Q and S. The coin for operating the device is illustrated in the drawings in solid and dotted lines and designated by letter T.

The operation of my invention will be readily understood and is as follows:— When the parts are in their normal positions, as shown in Fig. 1 of the drawings, a coin may be inserted in the chute and, coming in contact with the pawl R, will cause the same to tilt from the position shown in solid lines in Fig. 3 to the position shown in dotted lines in the same figure, thus allowing the coin to be deposited in proper position upon the lateral projection G² of the member G in readiness to be utilized in the successful operation of the machine. When the coin comes in contact with the pawl, it tilts the latter, throwing the notch thereof out of engagement with the lug Q' and allowing the member Q to fall by gravity to its lowest limit and which position is illustrated in Fig. 4 of the drawings, thus forming an obstruction, preventing another coin being introduced until the lever F first shall have been depressed to again raise the member Q to its normal position out of the path of the coin. In Fig. 5 of the drawings, the lever is shown in its depressed position at its lowest limit, the depressing or swinging down movement of the outer free end of the lever causing the chute E to tilt forward, allowing the free end of the member S to tilt down to the position shown in Fig. 5 and which also will form an obstruction to the coin entering the chute until the lever has been returned to its normal position through the medium of the spring G³ and which is accomplished by the flange E' coming in contact with the curved edge of the finger S'. After the lever returns to its normal position, the pawl automatically returns to its normal position, the notch R³ thereof engaging the lug Q' and holding the parts in readiness to be again operated by the insertion of a second coin.

By the provision of the device shown and described, it will be noted that means is provided as a safeguard so that only one penny may be inserted in the machine at the same time, making it necessary to press the lever and operate the machine before a second coin may be inserted for another operation of the machine.

What I claim to be new is:

1. An attachment for coin-controlled machines comprising, in combination with a spring-pressed, pivotal plate adapted to support a coin and a chute movable with said plate, a lever having pivotal connection with said plate, a pivotal gravity coin arresting member pivoted to swing into the path of a coin adapted to be inserted in said chute, the

wall of said chute adapted to raise said member as the lever is depressed, and a pawl for holding the member in an elevated position and disposed in the path of the coin.

2. An attachment for coin-controlled machines comprising, in combination with a spring-pressed, pivotal plate adapted to support a coin and a chute movable with said plate, a lever having pivotal connection with said plate, a pivotal gravity coin arresting member pivoted to swing into the path of a coin adapted to be inserted in said chute, the wall of said chute adapted to raise said member as the lever is depressed, a pawl pivotally mounted upon the frame and disposed in the path of a coin to be inserted in the chute, said member having a projection engaged by the pawl to hold the member in an elevated position.

3. An attachment for coin-controlled machines comprising, in combination with a spring-pressed, pivotal plate adapted to support a coin and a chute movable with said plate, a lever having pivotal connection with said plate, a pivotal gravity coin arresting member pivoted to swing into the path of a coin adapted to be inserted in said chute, the wall of said chute adapted to raise said member as the lever is depressed, a pawl pivotally mounted upon the frame and disposed in the path of a coin to be inserted in the chute and provided with a notch, said member having a laterally projecting lug adapted to be engaged by the notched portion of the member to hold the latter in an elevated position.

4. An attachment for coin-controlled machines comprising, in combination with a spring-pressed, pivotal plate adapted to support a coin and a chute movable with said plate, two gravity coin-arresting members pivotally mounted upon the frame, a tilting pawl supporting one of said members and disposed in the path of the coin to be inserted in said chute, the other supported by the wall of the chute, and a lever having pivotal link connections with said plate.

5. An attachment for coin-controlled machines comprising, in combination with a spring-pressed, pivotal plate adapted to support a coin and a chute movable with said plate, two gravity coin-arresting members pivotally mounted upon the frame, a tilting pawl supporting one of said members and disposed in the path of the coin to be inserted in said chute, the other member provided with a finger disposed in the path of the wall of said chute, and a lever having pivotal link connections with said plate.

6. An attachment for coin-controlled machines comprising, in combination with a spring-pressed, pivotal plate adapted to support a coin and a chute movable with said plate, two gravity coin-arresting members pivotally mounted upon the frame, a tilting

pawl supporting one of said members and disposed in the path of the coin to be inserted in said chute, the other member provided with a finger disposed in the path of the wall of said chute, a lever having pivotal link connections with said plate, said gravity members having slots therein, and a stationary pin upon the frame passing through said slots.

10 7. An attachment for coin-controlled machines comprising, in combination with a spring-pressed, pivotal plate adapted to support a coin and a chute movable with said plate, said chute having an inclined 15 wall, a bracket secured to the frame, two gravity coin-arresting members pivotally mounted upon said bracket and provided

with slots, a pawl pivotally mounted upon said bracket and having a notch therein, a lug projecting from one of said coin-arresting members, a finger projecting from the other with an inclined edge disposed in the path of the inclined wall of said chute, said member having the lug thereon adapted to be raised by contact with said chute as it 20 tilts, while the member with an inclined finger is allowed to fall upon the tilting of the chute.

In testimony whereof I hereunto affix my signature in presence of two witnesses.

HARRY D. YERXA.
